UNITED STATES PATENT OFFICE.

MIKE COLLINS, OF SULPHUR SPRINGS, ARKANSAS.

SCRAPER OR EXCAVATOR.

SPECIFICATION forming part of Letters Patent No. 532,029, dated January 8, 1895.

Application filed June 2, 1894. Serial No. 413,267. (No model.)

To all whom it may concern:

Be it known that I, MIKE COLLINS, a citizen of the United States, residing at Sulphur Springs, in the county of Benton and State of Arkansas, have invented certain new and useful Improvements in Scrapers or Excavators; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 The special object of the invention is to make a scraper or excavator simple, durable and not easily got out of order.

Figure 1 of the drawings is a plan view of my self-loading, two-wheeled scraper or excavator; Fig. 2, a longitudinal vertical section thereof.

In the drawings, A represents the cart-frame pivoted on an axle B on which rotate the wheels C C.

25 D is the cart-body pivoted near its upper rear corners on the axle B and just within the frame A, the bottom being provided in front with the scraper E.

30 F are upwardly turned hooks attached to the sides and near the front end of the body D, the same having a series of opposite holes e e in any registering two of which may be secured the screwbolt f held by a nut f'. These screwbolts, in whatsoever holes placed, 35 rest on the sides of body D and thereby regulate the depth of cut of the scraper E. At the bottom of the rear end of the body, I hinge the end-gate G which may be closed by a cord or a chain g with its upper end attached to any 40 convenient point, while it is automatically locked or fastened by the lever latch H fulcrumed on the top of body D. The latch H has a laterally and upwardly projecting arm h by which it may be disengaged by hand or 45 otherwise.

I is a curved rack attached longitudinally to the top of body D and J a ratchet-bar or 50 detent pivoted thereto, to engage automatically the cross-plate a, on the rear of frame

A, so as to hold the body D at any point to 50 which it may have been elevated.

K is a lever to which is pivoted the bail k which works in the teeth of the rack I, said teeth inclining toward the front. This lever is fulcrumed on a cross-rod L on which may 55 be used the set-nuts M M to prevent any lateral movement of the lever.

In order to empty the earth which accumulates in the body D, the driver pulls back the lever K so as to raise the front and lower the rear 60 end of the body, when the pivoted rackbar J automatically engages plate a to hold it. The lever can then be made to take one or more new holds upon the rack I until the body D is tilted to the desired extent. By lifting the 65 detent J, the body drops back into its original position so that the operation of scraping or excavating may proceed. With this scraper, no stoppage of the team is necessary in order to unload or in preparing to load up 70 after a discharge.

Having thus described all that is necessary to a full understanding of my invention, what I claim as new, and desire to protect by Letters Patent, is—

75 1. A two-wheeled scraper or excavator with a body pivoted to the axle at its rear upper corners just within the frame A and provided with pins adjustable in hooks at the front end of each side as and for the purpose set 80 forth.

2. In two-wheeled scrapers or excavators, a rear-pivoted body with a bottom-pivoted end-gate and a pivoted latch-lever as and for the purpose described.

85 3. The rear-pivoted body of a scraper or excavator carrying on top a stationary ratchet and pivoted rack-bar whose subjacent teeth form a detent, in combination with the lever K carrying the pivoted bail k and the rear 90 crossplate a of the frame A; as and for the purpose set forth.

In testimony whereof I affix my signature in presence of two witnesses.

MIKE COLLINS.
